Primary Examiner—M. N. Pandozzi(74) *Attorney, Agent, or Firm*—Meroni & Meroni, P.C.; Charles F. Meroni, Jr.(57) **CLAIM**

The ornamental design for the soup and cereal bowl, as shown and described.

DESCRIPTION

FIG. 1 is a perspective side view of the soup and cereal bowl;

FIG. 2 is a cross sectional view thereof taken along line 2—2 of FIG. 3;

FIG. 3 is a plan top view of the soup and cereal bowl; FIG. 4 is a perspective bottom view of the soup and cereal bowl; and,

FIG. 5 is a perspective view thereof.

The broken line showing of a base, lid, and spoon is for illustrative purposes only and forms no part of the claimed design.
